DOOR LOCKING DEVICE

Samuel E. Cochran, Kansas City, Mo.

Application July 15, 1932, Serial No. 622,675

7 Claims. (Cl. 292—338)

The present invention relates to door locking means, and aims to provide an improved device adapted to be carried by a door for movement into either inoperative position, or into operative position for holding the door partly ajar, or for securely locking the door in completely closed position.

Accordingly the improved door locking device comprises a bracing or locking arm which is mounted upon the inner face of the door and adapted to be raised and held latched in its inoperative position, when not in use, or conveniently unlatched and lowered for its bracing or locking function, for which purpose there is provided a channel or track device set in the floor for engagement with the lower end of the bracing or locking member and limiting the movement thereof according to the distance the door is to be maintained open, and also providing means for locking engagement with the bracing or locking member, whereby the door is securely locked in its closed position.

It is also an object of the invention to provide not only a practical and efficient means for accomplishing the purposes of the device as an effective and reliable door securing appliance, but also a construction which is of a neat design and attractive appearance, convenient in its operation, and offering no obstruction to the normal movements of the door, when the device is not in use.

With the foregoing general objects in view, as well as various minor details of improvement as will appear in the course of the detail specification, the invention will now be described by reference to the accompanying drawings, illustrating certain forms of construction which have been found practical for the embodiment of the improvements, after which those features and combinations deemed novel will be particularly set forth and claimed.

In the drawings—

Figure 1 is an elevation, illustrating a door equipped with an appliance embodying the present invention;

Figure 2 is a side elevation of the same, with dotted lines representing the device raised into inoperative position;

Figure 3 is a horizontal sectional view, representing a section taken on the line 3—3 of Figure 1;

Figure 4 is an enlarged sectional detail view representing a section on the line 4—4 of Figure 2;

Figure 5 is a section on the line 5—5 of Figure 4;

Figure 6 is a similar sectional view, but illustrating the door bracing and locking member in locked position;

Figure 7 is a plan view of the floor-track or channel device;

Figure 8 is a detail representing a section on the line 8—8 of Figure 5;

Figures 9 and 10 are sectional details, taken on the lines 9—9 and 10—10, respectively, of Figure 7;

Figure 11 is a sectional detail of one end of the channel or track member in closed condition;

Figure 12 is a sectional detail view, showing the latch device carried by the door, in engagement with the bracing or locking member, when the latter is raised to inoperative position;

Figure 13 is a perspective detail of the hinged end of the door brace or locking member;

Figures 14 and 15 are elevations, similar to Figures 1 and 2 respectively, but showing a modified construction;

Figure 16 is an enlarged detail plan view, showing the modified form of channel or track member for the door bracing or locking member;

Figure 17 is a longitudinal section, representing a section on the line 17—17 of Figure 16;

Figures 18 and 19 are detail sections, taken on the lines 18—18 and 19—19, respectively, of Figure 17;

Figure 20 is a perspective detail of the hinged end of the modified form of the brace or locking member;

Figure 21 is a detail of the modified form of the latching device carried by the door; and

Figure 22 is a vertical sectional detail of the same, with the door-bracing or locking member in raised and latched position.

Referring now to the drawings in detail, and primarily to Figures 1 to 13, these disclose the appliance in operative relation to a door 24 of the usual form, to the lower and one side portion of which the bracing or locking arm 26 is attached by means of a suitable plate 27 and screws 28. This plate 27 is provided with a pair of spaced lugs 29 for the mounting of a suitable pivot pin 30, on which is pivotally mounted a bracket member 31 formed with end lugs 32 for the mounting of a pivot pin 33 for carrying the upper cylindrical terminal 34 of the arm 26, as clearly illustrated in Figures 1, 2, 3, and 13. The pivot pins 30 and 33 being substantially at right angles to each other, it is thus apparent that the arm 26 is afforded a universal pivotal movement relative to the door 24. For maintaining the plates 27 and 31 normally in sub-

stantially parallel relation, suitable coil springs 35 are interposed between the ends of said plates, thus yieldingly permitting the rocking of the plate 31 about the axis of the pivot pin 30.

5 The other end of the arm 26 is formed with an angularly arranged and enlarged terminal in the form of a suitably shaped head 37 for travel along a channel or track member which comprises a housing 38 adapted to be set in the floor 10 39, with the top of the housing flush with the floor surface, as represented in Figures 1 and 2. The opening into the interior of the channel or track-housing 38 is normally closed by a pair of hinged leaves 40, each hinged along one side 15 of the housing as indicated at 41 and adapted to be held in horizontal or normally closed position by means of a coil spring 42 connecting fingers 43 projecting from the leaves 40 through suitably curved slots 44 in one end of the housing 20 38 (see Figure 9). The leaves 40 are also designed to be latched in closed position by means of a movable latch bar 46 provided with laterally projecting fingers 47 extending through curved slots 48 in the sides of the housing 38 into engagement with a pair of lugs 49 at the sides of the housing, which lugs also form seats for coil springs 50 carried by said fingers 47—see Figure 7. These springs serve to support the latch bar in latching position, as illustrated in 25 Figure 6, while yielding to allow the latch bar to be forced downward and rearwardly when the leaves 40 are forced open, as hereinafter explained. One of said leaves 40 also carries a latch pin 52 on its under face, which pin is actuated by a coil spring 53 into engagement with a 30 recess 54 in the latch bar 46 (see Figure 11), while the other end of said pin slides through an opening 55 in the leaf 40 for entering a slight depression 56 in said leaf, and permitting the pin 52 to be actuated by engagement with the 35 head 37 of the arm 26, in forcing the latch bar 46 downwardly and rearwardly out of latching position.

As illustrated in Figure 7, the opening into the track or channel member 38, and the shape of the hinge leaves 40, are such as to provide an enlarged opening 60 approximately midway between the ends of the track member, through which the head 37 may be inserted, on opening 38 of the hinge leaves 40, as shown in Figure 8, after which said head 37 may be moved in either direction, that is, toward either end of the track or channel member 38, while withdrawal of the head 37 is permitted only at said central opening 60. Movement of the head 37 toward the rear end of the track member 38 allows the door to be secured and braced in partly open position, as represented in Figure 3, with the head 37 of the brace arm 27, located as shown in Figures 4 and 5 and being prevented from removal from the housing by reason of the narrower size of the end 61 of the track or channel opening, as illustrated in Figure 7.

The head 37 is adapted to be moved also to the opposite end of the track or channel member for locking the door in entirely closed position, as represented in Figures 2 and 6, it being noted that the sides of the head are moderately curved to compensate for any lateral swing of the arm 26, in company with the movement of the door. When in the position shown in Figure 6, the head 37 may be securely locked by means of a locking bar 65 engaging a locking recess or socket 66 in the bottom of the housing member 38. The locking bar 65 is mounted for

vertical sliding movement in the head 37 and formed with teeth 67 for engagement with a cog wheel 64 which in turn engages teeth 68 on a vertically sliding bar 69 having its upper end also provided with teeth in engagement with a cog or pinion 70 designed for engagement by a cog segment 71 having an operating or handle portion 72 projecting outwardly from the recess 73 in the arm 26 and head 37 which contains said operating parts 65—71, as illustrated in Figure 85 6. By means of this mechanism, it is apparent that operation of the projecting arm 72, (as by means of the foot) the rotation of the cogs and consequent sliding of the rack bars will effect raising and lowering of the locking bar 65 as required for projecting it into or out of the recess or socket 66.

When it is desired to dispense with the use of the door locking arm or bracing functions, the arm 26 may be simply swung and raised into vertical position, as represented by the dotted lines in Figure 2, and the full lines in Figure 12, when its upper end will be automatically latched by means of a latching arm 75 formed with the bevel face 76 for engagement with the head 37 when the latter is swung into elevated position, thereby automatically rocking the arm 75 about its pivot 77 in a bracket 78 designed to be secured by means of screws 79 to the inner face of the door 25. The arm 75 is formed with a tail piece 80 projecting within the bracket and engaged by a coil spring 81 tending to rock the arm 75 and maintain the same in yielding latching engagement with the lower or flat face of the head 37, as clearly illustrated in Figure 12. Obviously this 100 construction will also permit the unlatching of the arm 26 by simple pulling of the same outwardly away from the door, and from beneath the latch arm 75.

Referring now to Figures 14—22 of the drawings, these illustrate a somewhat modified form of the construction, though in the main characterized by substantially the same functions as the construction previously described. That is to say, the door bracing or locking arm 26' is provided with a universal-jointed connection with the door, the construction for which comprises a forked terminal 85 pivotally connecting with the opposite sides of a collar or ring 86 slidably as well as rotatably mounted upon a vertical pin 120 87 mounted between two vertically spaced lugs 88 on the face of a bracket plate 89 secured, by means of screws 90, to the inner face of the door, as illustrated in Figures 14 and 15. The outer end of the arm 26' is formed with a head terminal 37' for insertion within a channel or track member, which in this instance comprises a housing 38' set in the floor 39 and covered by a floor plate 91 formed with a longitudinal opening 92 having the enlarged portion 93 permitting insertion of the head 37' into the space 94 inside the housing member 38'. Also mounted centrally within this housing member 38' is a longitudinal rod 95 operating in a central passage 96 containing a coil spring 97, which acts to force 125 said rod 95 normally forward into engagement with a stop 98 projecting inwardly from the opposite end of the housing 38' into approximately vertical alinement with the forward end of the opening 93 (see Figure 17). The rod 95 is designed for engagement with the head 37', which is formed with an opening 100 which is of somewhat oval shape in cross section for accommodating said rod, the head 37' being also of sufficiently convex contour to permit the necessary 130 140 145 150

- angular movements of the arm 26' as required for accommodating corresponding movements of the door. The rod 95 is also formed with an upwardly projecting finger 102, whereby the rod 5 may be retracted when the head 37' is inserted into the track member, the arm 26' and head 37' having a suitable recess 103 for clearing said finger 102 as the head 37' moves backward within the space 94 inside the housing 38'. 80
- 10 The provision made in this form of the construction for maintaining the arm 26' elevated when not in use, as illustrated in Figure 15, comprises a latch arm or hook 106 carried by a shaft 107 mounted vertically in spaced bearing lugs 108 carried by a bracket plate 110 attached to the door by screws 111 (see Figure 22). The opposite ends of the shaft 107 are formed with teeth 112 for engagement by corresponding teeth 114 formed on a pair of pins or rack bars 115 85
- 15 slidably mounted in horizontal passages 116 provided in the bearing lugs 108. The arrangement is such that as the arm 26' is swung upward, it will engage the lower rack bar or pin 115 and rotate the shaft 107 in the proper direction for 90
- 20 swinging the latch hook or arm 106 automatically into engagement with the arm 26', and thus secure it in its inoperative position. On the other hand, for the release of the arm 26', pressure by 95
- 25 the operator upon the upper pin or rack bar 115 will produce opposite movement of the shaft 107, and disengage the hook 106 from the arm 26', as required for release of the same into position for use. For engaging the head 37' within the floor track or channel, the rod is retracted by means of 100
- 30 its pin 102, sufficiently to allow the rod 95 to be engaged with the opening 100 in the head 26'; thereafter, on releasing the finger 102, the rod 95 will serve to prevent withdrawal of the head 37' from the floor track or channel, and the spring 105
- 35 97 will cushion any movement of the door and its bracing arm 26' in a rearward or opening direction, due to the engagement of the finger 102 within the recess 103 as shown in Figure 17.
- It will therefore be apparent that I have 110
- 40 devised a practical, efficient, and secure door bracing and locking construction, adapted to fulfill all the stated objects of the invention, as well as to take the form of a neat and attractive appliance for attachment to the door, in the manner 115
- 45 illustrated.
- It is of course to be understood that either form 120
- 50 of construction permits securing of the door in a partly open position, as is often desired to guard against the entrance of any intruder; furthermore, it is obvious that the improved construction 125
- 55 enables the door to be securely and effectively locked in closed position, by the locking means provided for the head of the locking arm within the floor track or channel, as illustrated in Figure 6.
- It is to be understood that while I have 130
- 60 illustrated and described what I now regard as certain of the most practical and efficient forms of construction for embodying the proposed improvements, I desire to reserve the right to make 135
- 65 whatever changes or modifications may fairly fall within the scope of the following claims.
- Having described my invention, what I claim 140
- 70 to be new and desire to secure by Letters Patent is:
1. Door securing means comprising an arm provided with an enlarged terminal head, a floor 145
- track or channel member having a longitudinal opening flush with the floor surface, a part of said opening being of a size sufficient to admit said head and the remainder of said opening being relatively narrower to prevent withdrawal of the head, and hinged cover elements having a combined contour fitting said opening and provided with means for maintaining the same normally in closed position. 80
2. Door securing means comprising an arm provided with an enlarged terminal head, a floor track or channel member having a longitudinal opening flush with the floor surface, a part of said opening being of a size sufficient to admit said head and the remainder of said opening being relatively narrower to prevent withdrawal of the head, and hinged cover elements for said opening provided with means for automatically latching said cover elements in closed position. 85
3. Door securing means comprising an arm provided with an enlarged terminal head, a floor track or channel member having a longitudinal opening flush with the floor surface, a part of said opening being of a size sufficient to admit said head and the remainder of said opening being relatively narrower to prevent withdrawal of the head, hinged cover elements for said opening provided with means for automatically latching said cover elements in closed position, and means engageable by said head for effecting unlatching of said cover elements. 90
4. Door securing means comprising an arm provided with a terminal head, a floor track or channel member having a longitudinal opening flush with the floor surface and provided with a locking recess in the bottom of said member, a vertically movable locking bar carried by said head for locking engagement with said recess, and a pivotal cog segment provided with connections for raising and lowering said locking bar. 100
5. Door securing means comprising an arm provided with a terminal head, a floor track or channel member having a longitudinal opening flush with the floor surface and provided with a locking recess in the bottom of said member, and a vertically movable locking bar carried by said head for locking engagement with said recess and provided with rack and cog means including an exterior pivotal handle element operable for raising and lowering said bar. 105
6. A keeper structure for door locking arms comprising, a channel member having a longitudinal opening for receiving the end of the locking arm, hinged cover plates having means for maintaining the same in normally closed relation to said opening, and a latch bar movable normally into engagement with the interior faces of said plates for latching the latter in closed position. 110
7. A keeper structure for door locking arms comprising, a channel member having a longitudinal opening for receiving the end of the locking arm, hinged cover plates having means for maintaining the same in normally closed relation to said opening, a latch bar movable normally into engagement with the interior faces of said plates for latching the latter in closed position, and a latch-disengaging element carried by one of said plates for engagement by the locking arm for actuating said bar out of latching position. 115

SAMUEL E. COCHRAN.
